UNITED STATES PATENT OFFICE.

WILBERT MAPLE, OF COLLINSVILLE, OKLAHOMA.

GRAIN-SEPARATOR.

1,260,227.

Specification of Letters Patent. Patented Mar. 19, 1918.

Application filed February 6, 1917. Serial No. 146,972.

To all whom it may concern:

Be it known that I, WILBERT MAPLE, a citizen of the United States, residing at Collinsville, in the county of Rogers and State of Oklahoma, have invented new and useful Improvements in Grain-Separators, of which the following is a specification.

This invention relates to threshing, and more especially to grain separators; and the object of the same is to separate a larger percentage of grain from the straw before the latter is delivered to the stacker.

This object is carried out by mounting beaters at the delivery end of the straw carriers, and suspending behind each beater a grate of peculiar construction. Details of the preferred embodiment of the machine are set forth in the following specification, reference being had to the accompanying drawings wherein:—

Figure 1 is a general sectional view of this separator complete, showing in dotted lines how one door in the top of the casing may be raised and the grate swung upward through the door-opening.

Fig. 2 is an enlarged perspective detail of one of the grates.

Fig. 3 is an enlarged perspective detail of one of the beaters, and

Fig. 4 is a similar detail of one of the vibrators.

In the drawings the numeral 1 designates broadly the casing in which is located mechanism yet to be described, but I have considered it necessary to show in detail only the upper part of the casing, the same in the present case having two door-openings in each of which as at 2 is hinged a door 3, capable of being thrown to the rear to expose the interior of the casing from above, as indicated in Fig. 1. Within the front portion of the casing is the threshing mechanism T, which includes a cylinder and concave as usual, and the machine is otherwise provided with the customary elements forming no part of the present invention. In the present instance I have shown three grain carriers, 4, 5 and 6, each of the endless belt type and with its upper side moving obliquely rearward and upward as indicated by the arrow. The rear or delivery end of one carrier overlies the front end of the next, and between them is disposed a check board 7, the same preferably having at each end a hook 8 engaged with a suitable member in the side wall of the casing

so as to hold the board in position to prevent the material delivered by one carrier from falling off the front end of the next carrier. Beneath the upper side of each carrier is disposed a vibrator, shown in Fig. 4 as consisting of a series of oblong or oval rollers 9 mounted upon a shaft which is rotated at suitable speed, and by this means the upper side of the carrier is knocked or vibrated at rapid intervals to toss or loosen the straw passing over the same from the threshing mechanism.

Coming now more particularly to the details of the invention, in the rear of each carrier is hung a grate whose details are best seen in Fig. 2. By preference it is made up of a pair of side bars, each of which has an eye 10 at its upper extremity, is straight as at 11 throughout its upper portion, and is curved in the rear as at 12 throughout its lower and probably its major portion; and these side bars are connected by transverse grate bars 13 which are coextensive with the curved portions and need not exist throughout the straight portions, although it would do not harm if they did. Secured behind the major portion of this structure is a shield 14 of sheet iron or the like. The entire grate is of a size to swing through the opening left by one of the doors 3 in the top of the casing, when said door is opened as seen in Fig. 1, and for this purpose the door is preferably hinged as at 2 at the rear edge of the opening whereas the grate is hinged at 15 at the front edge of the opening, the support pivotally connecting with the eyes 10 in any suitable manner. When it is desired to inspect, to clean, or to repair the grate, it is only necessary to open the door and swing the grate outward onto the top of the casing 1. Doubtless the door-opening will be sufficiently large to allow the operator to crawl into the same or at least to reach through the same so that he will have access to other parts on the interior of the machine.

Coating with each grate is a beater whose detailed construction is best seen in Fig. 3. This beater may well be made of a board or plank 16, measuring about an inch thick and fourteen inches wide, and the same is mounted rigidly on a shaft 17 extending longitudinally through its transverse center and having a pulley 18 by which it is connected to the driving mechanism so as to impart a quite rapid rotary

movement thereto. The shaft is journaled in bearings in the sides of the casing which are so located that the beater as a whole stands within the curved portion of the 5 grate, or in other words, between such portion and the rear-end of the carrier, and out of contact with both. The grate is so hung that its weight causes it to swing normally toward the beater, but it is kept from 10 swinging actually into contact therewith by suitable means such as stop pins 20 in the sides of the casing and against which the lower ends of the side bars strike, as indicated in Fig. 1.

15 Experience has proven that a grain separator of this character may be run at a high rate of speed, whatever the character and condition of the grain being treated, and yet it will extract a larger percentage of kernels of grain from the straw than any separator with which I am familiar. From the 20 threshing mechanism the straw passes onto the first carrier, whereon it is tossed by the vibrating mechanism and carried upward 25 and rearward. Dropping off its rear end, it falls on the rapidly revolving beater, by which it is thrown against the rearwardly curved portion of the grate, or more accurately speaking, against the slatted or grated 30 portion thereof which stands directly behind the beater, is curved to conform with the cylindrical path through which the edges of the beater blade move, and yet is held out of contact with the beater by the 35 stop pins. The more rapid the revolution of the beater and the greater the volume of material thrown by it against the grate, the farther the latter will be swung to the rear on its hinged support at 15 and therefore 40 the greater the space will be opened between the beater and the grate. This prevents choking of the parts, while always subject-

ing the mass to the blows of the beater which are necessary to extract the kernels. The latter pass through the grate bars 13 45 and strike the shield 14, by which they are deflected downward and, passing the check board 7, they fall onto the grain pan and are saved. Meanwhile the straw and chaff is caught by the check board and passed to 50 the next carrier by which it is raised, and the operation repeated. I have shown three carriers with two interposed mechanisms as described, but I do not wish to be limited in this respect. 55

What is claimed as new is:—

1. In a grain separator, the combination with an endless carrier whose upper side moves to the rear; of a grate pivotally supported at its upper end and with its lower 60 portion slatted and hanging behind the delivery end of said carrier, and a beater rotating in the space between the carrier and said slatted portion.

2. In a grain separator, the combination 65 with a pair of carriers whereof the rear end of one overlies the front end of the next, of a pendant, swinging grate whose lower portion is curved to the rear and hangs behind the delivery end of the first carrier, and a 70 beater rotating in the space between said carrier and curved portion.

3. The herein described grate for grain separators, the same comprising a pair of side bars whose upper portions are straight 75 and whose lower portions are curved to the rear, a series of transverse grate bars connecting the curved portions thereof, a sheet metal shield secured behind all the grate bars, and means for pivotally supporting the grate from the upper ends of its 80 side bars.

In testimony whereof I affix my signature.
WILBERT MAPLE.
